UNITED STATES PATENT OFFICE.

EDWARD M. HEWLETT, OF SCHENECTADY, NEW YORK, ASSIGNOR TO
GENERAL ELECTRIC COMPANY, A CORPORATION OF NEW YORK.

DOUBLE-THROW ELECTRIC SWITCH WITH INDICATOR.

No. 833,208.

Specification of Letters Patent.

Patented Oct. 16, 1906.

Application filed July 11, 1903. Serial No. 165,105.

To all whom it may concern:

Be it known that I, EDWARD M. HEWLETT, a citizen of the United States, residing at Schenectady, in the county of Schenectady and State of New York, have invented certain new and useful Improvements in Double-Throw Electric Switches with Indicators, of which the following is a specification.

This invention relates to switches for electric circuits, and especially to those which shift the current from one circuit to another by what is commonly termed a "double-throw" construction. Such a switch is employed, for instance, as a controlling-switch for a high-tension motor-actuated oil-switch, which for prudential reasons must be located at a distance from the switchboard and operated by a motor-control circuit running to the switchboard, where it includes a small hand-switch. An installation of this kind is shown in the pending application of Hewlett and Button, filed January 15, 1902, Serial No. 88,757. The motor is controlled by two parallel circuits leading to a double-throw switch, and the arrangement is such that the two circuits must be used alternately.

My invention consists in an improved switch for such a system, and it is so constructed as to advise the operator which circuit he must employ when he wishes to operate the switch.

In the accompanying drawings, Figure 1 is a longitudinal section of a switch embodying my improvements. Fig. 2 is a top plan view of the same. Fig. 3 is a bottom plan view. Fig. 4 is an elevation of the handle-hub and index. Fig. 5 is a plan of the detent-plate; and Fig. 6 is a detail cross-section on the line 6 6, Fig. 1.

In a suitable insulating support, plate, or panel 1 are mounted two signal-lamps 2, each in a separate circuit, and adjacent to them is a recess in the panel, in which is a flanged cup-shaped nut 3, screwed upon a tubular neck 4, which projects from a frame 5, clamped by the flange of said nut against the back of the panel. The frame supports a plate 6 of insulation, below which are secured three spring-contacts 7 7^a 7^b, forming the terminals of the two control-circuits in which the lamps are included, contact 7 being common to both circuits.

A stem 8 is rotatably mounted in the tubular neck 4 and passes through the plate 6.

On its lower end is a disk 9 of insulation, whose periphery has a metallic rim 10, which forms a bridging contact and has three segmental lugs 11 11^a 11^b, the lug 11 being preferably longer than the others. The lugs and contacts are so arranged that normally they do not engage; but a quarter-turn of the stem will close a circuit from contact 7 either with contact 7^a through segment-lugs 11 11^a, or with contact 7^b through segments 11 11^b. To return the switch to its normal open position and retain it there yieldably, an arm 12 is rigidly secured to the stem, preferably by means of a sleeve 13, from which said arm projects.

The arm engages with a resilient retainer, preferably a helical spring 14 encircling the stem and having its ends overlapping the opposite sides of an abutment 15 on the frame 5 and clasping the arm 12 between them. A movement of the arm 12 in either direction carries one end of the spring with it, the other being arrested by the abutment. The energy thus stored in the spring is sufficient to return the switch to the "off" position.

A handle 16 is fastened to the upper end of the stem 8, and between the hub of the handle and the top of the tubular neck 4 is a detent-plate 17, attached to said neck. Above said plate and concentric with the stem is an annular portion 18 of an index 19, which extends beyond the cup-shaped nut 3 toward the lamps 2. The portion 18 of the index has a lug 20, which lies between two shoulders 21 on the hub of the handle, as shown in Fig. 4. The space between the shoulders is greater than the width of the lug, so that there is a certain amount of lost motion. When the handle is turned, one of the shoulders strikes the lug and carries the index around as far as the handle is moved, preferably such an angular distance that the index will point at one of the lamps. When the spring 14 returns the handle to its normal position, the lost motion leaves the index unmoved, but brings the opposite shoulder 21 close to the lug 20, so that the index will be carried to its other position when the handle is turned to close the other circuit.

In order to prevent accidental displacement of the index, a detent is provided, preferably one or more small rounded projections or knobs 22 on the under face of the index, adapted to enter sockets 23 in the detent-

plate 17. A spring 24 between the handle-hub and the index keeps the knobs yieldingly in the sockets. A stop 25 on the frame and shoulders 26 on the sleeve 13 limit the angular movement of the handle.

In accordance with the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. The combination with an electric switch, of an operating-handle therefor, an indicator having a movement concentric with that of the switch, and lost-motion-transmitting devices between said indicator and switch.
2. The combination with a double-throw switch, of means for yieldingly holding it in the "off" position, and means for visually indicating the circuit last closed actuated directly by the switch.
3. The combination with an electric switch having a rotary stem, of an indicator having a movement concentric with said stem and independent of said switch, and a lost-motion connection between said stem and indicator.
4. The combination with an electric switch having a rotary stem, of a rotary indicator concentric with said stem and having a movement independent of said switch, and a lost-motion connection between said stem and indicator.
5. The combination with an electric switch having a rotary stem, of a rotary indicator having a movement independent of said switch, a lost-motion connection between said stem and indicator, and a yielding detent for said indicator.
6. The combination with an insulating-plate, of a U-shaped frame having a tubular neck projecting through said plate, a stem rotatable in said neck, co-operating contacts on said stem and frame, and a cup-shaped nut on said tubular neck bearing against the opposite sides of the insulating-plate.
7. The combination with an insulating-support, of a U-shaped frame having a tubular neck projecting through said support, a plate of insulation secured to said frame, contacts on said plate, a stem rotatable in said neck, a bridging contact on said stem, and a cup-shaped nut on said tubular neck bearing against the opposite side of the insulating-plate.

8. The combination with an insulating-support, of a U-shaped frame having a tubular neck projecting through said support, a plate of insulation secured to said frame, three contacts on said plate, a rotatable stem in said neck, an insulating-disk on said stem, a metallic rim on said disk having lugs adapted to co-operate with said contacts, and a cup-shaped nut on said tubular neck bearing against the opposite side of the insulating-plate.

9. In an electric switch, the combination with an insulating-plate having a recess therein, of a U-shaped frame having a tubular neck projecting into said recess, a cup-shaped flanged nut screwed on said neck, a stem rotatable in said neck, co-operating switch-contacts on the frame and stem, means for yieldingly resisting the movement of the stem either way from a central position, and an indicator denoting which way the stem was last turned.

10. In an electric switch, the combination with a tubular support, of a stem rotatable therein, an index having an annular portion concentric with said stem and provided with a lug, a handle on the stem, and shoulders on the handle to engage with said lug.

11. In an electric switch, the combination with a tubular support, of a stem rotatable therein, an index having an annular portion concentric with said stem and provided with a lug, a handle on the stem, shoulders on the handle to engage with said lug, a detent-plate secured to the support, below the index, and a spring abutting between the index and the handle.

12. In an electric switch, the combination with a tubular support, of a stem rotatable therein, an index having an annular portion concentric with said stem and provided with a lug, a handle on the stem, shoulders on the handle to engage with said lug, a detent-plate secured to the support and containing sockets, knobs on the annular portion of the index, and a spring for keeping said knobs yieldingly engaged with said sockets.

13. The combination with an insulating-plate, of a U-shaped frame having its parallel portions extending away from said plate and having a tubular neck projecting from its central portion through said plate, a stem rotatable in said neck, and co-operating contacts on said stem and frame.

In witness whereof I have hereunto set my hand this 9th day of July, 1903.

EDWARD M. HEWLETT.
